COPY HOLDER FOR USE WITH TYPE-WRITERS, CALCULATING, AND LIKE MACHINES

Thomas Lewis Coppelock, Buenos Aires, Argentina

Application September 13, 1937, Serial No. 163,666
In Great Britain September 17, 1936

10 Claims. (Cl. 120—28)

This invention relates to a copy holder for use with typewriters, calculating and like machines.

The main object of the invention is to provide a copy holder which is held in position at the side of the machine by and against the weight of the machine, thereby to enable a very simple and quickly mounted holder to be economically constructed, which can be quickly removed when desired, and which, in position, holds the copy upright and at a convenient distance before the eyes for comfortable reading without strain and without the necessity for undue twisting of the neck. The term "upright" includes various positions tilted back from the vertical, and is not restricted to a vertical position, the angle at which the copy is held being that most convenient for sighting.

A subsidiary object of the invention is to provide means for clamping the copy holder in position against the weight of the machine.

A further object is to provide means for adjusting the copy holder as to height for cooperation with machines the frames of which are at different heights from a supporting surface, i. e. they may have relatively high or low feet.

Another object of the invention is to provide means for mechanically locking the holder to the machine frame so that it cannot be accidentally displaced.

Other objects of the invention provide for adjusting the sighting angle at which the copy is held, simple methods of fixing and holding the copy on the holder, and of giving a line guide whereby the matter of the copy can be easily and accurately read from line to line.

The various features of the invention will appear from the following description of one embodiment taken in conjunction with the accompanying drawing, wherein:

Figure 1 is an elevation of the copy holder mounted in position at the side of a typewriter, the view being taken from the front of the machine.

Figure 2 is a detail plan of the fulcrum block end of the copy holder, the copy supporting plate of the bracket being omitted, and

Figure 3 is an elevation partly in section along the line III—III of Figure 2.

Figure 4 is a detail view of a modified form of fulcrum means.

The embodiment shown consists of a metal fulcrum block 1 of convenient dimensions. The block is of right angle triangular shape providing a flat end face 2 which is inclined to the longitudinal axis of the block and which forms an

abutment for location against the side 3 of the machine frame so that the block is inclined lengthwise towards the front of the machine as will be clearly understood by reference to Figure 2. The block has a flat base 4 which rests on the surface 5 on which the machine (shown in chain dot lines) is supported. In the embodiment illustrated the fulcrum block is constructed for disposition at the left side of the machine frame, but it will be clear that if the inclination of the end face 2 is made opposite to that shown, the block can be used at the right hand side of the machine.

Any convenient inclination may be given to the end face, but in practice it is found that it can advantageously be at an angle such that the longitudinal axis of the block will be disposed at an angle within 45 to 60 degrees to the side of the machine frame.

Within the block and extending longitudinally thereof from the inclined abutment face 2 to the opposite face 6, is a passage 7 having two fulcrums 8 and 9 which are at different levels with respect to the base 4 of the block, as shown in Figures 1 and 3.

The other part of the copy holder consists of a bracket comprising a flat plate 10 at the bottom end of which is fixed a laterally projecting lever arm 11 having a flat portion 12 which can be passed through the passage 7 of the block and be supported on one of the fulcrums 8 and 9, the end 13 of this flat portion projecting from the block so as to engage under the side 3 of the machine frame; this side 3 is raised from the supporting surface 5 by reason of the usual feet provided on the machine. Due to the weight of the bracket on the side of the fulcrum remote from the machine, the end 13 of the arm 11 will lever up against the weight of the machine, and the bracket will thus be supported in an upright position alongside the machine and due to the inclination of the block with respect to the side 3 of the machine frame, the bracket will have a corresponding inclination providing a convenient position for reading copy supported on the plate 10.

The provision of a plurality of fulcrums—there may be more than two as shown—enables the copy holder to be adjusted to machines the side frames 3 of which are at different heights from the supporting surfaces, due to their feet being of different relative heights. By inserting the lever arm 11 into the passage 7 so that it rests on the appropriate fulcrum, it can be held by the weight of the machine in a substantially 35

horizontal position, thereby to ensure that the holder is retained properly in position.

As an additional means of securing the holder in position alongside the machine, the fulcrum block 1 is provided with an adjustable clamping device which applies pressure to the lever arm 11 to clamp the block down to the supporting surface 5 against the weight of the machine. Conveniently, such clamping device takes the form of a screw 14 which screws through the top of the block 1 so as to engage the arm 11 on the side of the fulcrum (8 or 9) remote from the side 3 of the machine, the upper fulcrum 8 having a hole 15 (tapped, if desired) through which the screw 14 can pass, when the lever arm is resting on the lower fulcrum 9. Greater leverage may be exerted by the screw 14, if the fulcrums 8 and 9 are disposed nearer the inclined abutment face 2 than they are in the embodiment shown.

For purposes of strength, the bracket is braced by a stay 16 connected between the lever arm 11 and the back of the copy support plate 10, and the portion of the lever arm connecting the flattened end portion 12 to the plate 10 is of L or channel section.

Associated with the lever arm and extending across the front of the plate is an upstanding flange 17 which forms a channel for the support of the lower end of the copy matter, this flange forming part of the lever arm or an extension of the plate 10.

A line guide and clip for retaining the copy in place on the plate 10 may take any suitable form; in the embodiment shown, a bar 18 serves this purpose being slidably mounted on the plate by having turned over ends which embrace the sides of the plate and one or each of which have a screw 19 for fixing the bar in position. Alternatively, the bar may be slidably mounted at one end only and may be pivoted to lift up; thus it can have a sleeve at one end which slides on a rod, being retained in adjusted position by a screw.

It will be seen that the arm 11 when mounted in the fulcrum block, 1, is a two arm lever of which the long arm carries the copy support plate 10, and is of such a length that the latter is disposed clear of the over-run of the carriage of the typewriter or other machine alongside which the copy holder is mounted.

Various modifications or additions may be made in the constructional details without departing from the spirit of the invention. For instance, each fulcrum may be mounted in a separate passage through the block 1, or with a view to providing greater adjustment as to the height of the fulcrum, the fulcrum may consist of a pin 21 (Figure 4) which can be inserted into one of a number of holes 22 made in the outer wall 20 of the block, there being a corresponding number of holes (tapped, if desired) in the opposite wall of the block to receive the end of the pin.

In the embodiment illustrated the copy support plate 10 is held in an upright position and at a rearward tilt for convenient sighting. Provision may, however, be made for enabling the tilt of the plate 10 to be adjusted and/or its angle with respect to the machine to be altered independently of the block.

In cases when the typewriter and like machine is placed in a tray, then the short arm of the lever arm, i. e. the flattened portion 12, will be downwardly cranked to pass over the edge of the tray and under the side of the machine.

I claim:—

1. A copy holder for typewriters, calculating and like machines comprising a bracket for supporting the copy, and having a laterally projecting lever arm, and a fulcrum block for disposition at the side of the machine, with said lever arm supported thereon and having an end disposed under the frame of the machine so that the bracket is held by the weight of the machine in an upright position.

2. A copy holder as set forth in claim 1, in combination with adjustable means which engage the lever arm on the side of the fulcrum remote from the machine to apply pressure to the block against the weight of the machine whereby the bracket and block are clamped to the surface on which it rests.

3. A copy holder for typewriters, calculating and like machines comprising a fulcrum block for disposition at the side of the machine and having an inner fulcrum, and a bracket for supporting the copy, said bracket being provided with a laterally projecting lever arm passing through the block so that it is supported by the inner fulcrum and has its end disposed under the machine frame.

4. A copy holder for typewriters, calculating and like machines comprising a fulcrum block for disposition at the side of the machine, a bracket for supporting the copy, said bracket being provided with a laterally projecting lever arm passing through the block so that its end can be disposed under the machine frame, and means within the block by which the lever arm can be supported and fulcrumed at different levels in relation to the bottom of the block.

5. A copy holder as set forth in claim 4, in combination with a clamping screw passing through the top of the block on the side of the fulcrum remote from the side of the block which lies adjacent the machine, said screw engaging the lever arm to press its end tightly under the machine against the weight thereof and thereby clamp the block to the surface on which it rests.

6. A copy holder for typewriters, calculating and like machines, comprising a fulcrum block for disposition at the side of the machine, a bracket for supporting the copy, said bracket being provided with a laterally projecting lever arm passing through the block so that its end can be disposed under the machine frame, a plurality of fulcrums within the block by which the lever arm can be supported and fulcrumed at different levels in relation to the bottom of the block, and adjustable means on the block for pressing on the arm to lever it about the fulcrum against the weight of the machine.

7. A copy holder for typewriters, calculating and like machines, comprising a fulcrum block for disposition at the side of the machine, a bracket for supporting the copy, said bracket being provided with a laterally projecting lever arm passing through the block so that its end can be disposed under the machine frame, a fulcrum within the block for supporting the lever arm, means for adjusting the height of the fulcrum, and adjustable means on the block for pressing on the arm to lever it about the fulcrum against the weight of the machine.

8. A copy holder for typewriters, calculating and like machines, comprising a fulcrum block for disposition at the side of the machine, a bracket for supporting the copy, said bracket being provided with a laterally projecting lever arm, and means for mounting the lever arm on

the block so that it is inclined towards the front of the machine, including an inner fulcrum on which the lever arm rests with its end engaging under the machine frame, and a clamping screw 5 on the side of the fulcrum remote from the lever end for applying pressure to clamp said end firmly to the machine frame.

9. A copy holder for typewriters, calculating and like machines, comprising a fulcrum block 10 with an end face inclined to the longitudinal axis of the block for location against the machine frame, and a longitudinal passage through said block, a bracket for supporting the copy, said bracket being provided with a laterally project-

ing lever arm, fulcrum means for supporting the lever arm within said passage with its end engaging under the machine frame, and clamping means for applying pressure to hold said end firmly against the machine frame. 5

10. A copy holder for typewriting machines and the like, comprising a bracket for supporting the copy and including a lever arm, a block adapted to be positioned beside the frame of the machine and selective fulcrum means in the block 10 on which a portion of the said lever arm may rest when the end of the arm is engaged beneath a portion of the machine frame.
